(57) **CLAIM**

The ornamental design for a bathing apparatus, as shown and described.

DESCRIPTION

FIG. 1 is a front view of a bathing apparatus.

FIG. 2 is a back view of the design shown in FIG. 1.

FIG. 3 is a top view of the design shown in FIG. 1.

FIG. 4 is a bottom view of the design shown in FIG. 1.

FIG. 5 is a left side view of the design shown in FIG. 1.

FIG. 6 is a right side view of the design shown in FIG. 1; and, FIG. 7 is a perspective drawing of the design of FIG. 1 showing the front view.

The intermittent surface treatment shown in FIGS. 1, 2, and 7 is understood to continue throughout the region on which it is shown.
